Geo. S. Pindle, his Atty

UNITED STATES PATENT OFFICE.

D. AZRO A. BUCK, OF WATERBURY, CONNECTICUT.

WATCH.

SPECIFICATION forming part of Letters Patent No. 234,233, dated November 9, 1880.

Application filed April 5, 1880. (Model.)

To all whom it may concern:

Be it known that I, D. AZRO A. BUCK, of Waterbury, in the county of New Haven, and in the State of Connecticut, have invented certain new and useful Improvements in Watch-Cases; and I do hereby declare that the following is a full, clear, and exact description thereof, reference being had to the accompanying drawings, making a part of this specification, in which—

Figure 1 is a perspective view of the notched ring and cap separated from the case. Fig. 2 is a plan view of said case, showing said ring in position, and Fig. 3 is a like view of the same with the cap in place.

Letters of like name and kind refer to like parts in each of the figures.

The design of my invention is to furnish a more secure attachment for the notched ring and cap with the case, and a better bearing for the spring-wheel; to which end it consists, principally, in the combination of the notched ring provided within its outer face with a rabbet for the reception of the spring-wheel, the cap fitted upon and secured to said ring outside of said rabbet, and the spring-wheel placed between said parts, substantially as and for the purpose hereinafter specified.

It consists, further, in the means employed for combining said notched ring with the case-center, substantially as and for the purpose hereinafter shown.

It consists, finally, in the combination of said notched ring and cap, substantially as and for the purpose hereinafter set forth.

In the annexed drawings, A represents the center of a watch-case, in which is placed a watch-movement, B, that is pivoted centrally and rotates around its axis.

Within the rear side of the center A is placed a ring, C, that has within its inner edge notches, c, for engagement with stop mechanism, and is secured in position by means of a steady-pin, c', which projects radially from its periphery and fits into a corresponding opening, a, in said case-center, and a screw, c'', that passes from within through said ring and case-center at a point opposite to said steady-pin.

Within the outer face of the notched ring C is formed a right-angled groove or rabbet, c³,

which receives a plate, D, that holds a main-spring, E, and operates as a barrel and a winding-wheel for the same. Said plate or winding-wheel furnishes a bearing at its center for the rear pivotal bearing, b, of the movement B, upon which bearing is attached the inner end of said mainspring. The spring-wheel D is rotated only for winding the mainspring E, and for such purpose the rabbet c³ furnishes a sufficient bearing.

Fitted over and inclosing the mainspring E is a cap, F, which has the form shown in Fig. 1, and has a bearing at its edge, upon the outer face of the toothed ring C, outside of the rabbet c³, a sufficient space being left between said cap and the spring-wheel D for the free movement of the spring E. Said cap is secured to or upon said ring by means of two or more screws, f, which pass through the edge of the former and have their threaded ends contained within threaded openings in the latter. The cap and notched ring thus secured together and to the case cannot become displaced without violence, and by confining the mainspring and its wheel steadily in position furnish for the rear pivot, b, a firm bearing.

Having thus fully set forth the nature and merits of my invention, what I claim as new is—

1. The combination of the notched ring C, provided with the rabbet c³, the spring-wheel D, fitted into said rabbet, and the cap F, placed over said spring-wheel and secured upon said notched ring, substantially as and for the purpose specified.

2. The combination of the case-center A, provided with the radial opening a, with the notched ring C, having the radial steady-pin c' and screw c'', substantially as and for the purpose shown.

3. The combination of the notched ring C and cap F by means of the screws f passing through the latter into the former, substantially as and for the purpose set forth.

In testimony that I claim the foregoing I have hereunto set my hand this 27th day of March, 1880.

D. AZRO A. BUCK.
